Primary Examiner — Lauren D Mcvey(74) Attorney, Agent, or Firm — Jose Cherson Weissbrot(57) CLAIM

The ornamental design for a scratch-off RV map, as shown and described.

DESCRIPTION

FIG. 1 is a top plan view of a scratch-off RV map, showing our new design with a top scratch-off layer; and, FIG. 2 is a top plan view thereof, showing our new design with the top scratch-off layer removed.

The map is flat and has minimal thickness.

The “FXW” lettering and icon forming part of the disclosure is a registered trademark of Guangzhou Mibo Zhilian Technology Co. LTD.

1 Claim, 2 Drawing Sheets(56)
